TOOL FOR REMOVING LOCKING KEYS
FROM BRAKE ANCHOR BOLTS

Carl B. Wayrynen, Denver, Colo.

Application April 8, 1947, Serial No. 740,032

1 Claim. (Cl. 29—268)

1

This invention relates to a tool for removing locking keys from brake anchor bolts of automotive vehicles. On many makes of automobiles, trucks, and busses the brake shoes are mounted on eccentric anchor bolts which can be rotated to adjust the band clearance. The shoes are held in place on the bolts by means of flat, U-shaped keys which are forced into circumferential grooves in the bolts. It is exceedingly difficult to remove these keys, since they are relatively thin and in such close proximity to the brake assembly that they cannot be reached or gripped by conventional tools. They often become bent and distorted so that it is impossible to remove them with ordinary tools without completely demolishing the key.

The principal object of this invention is to provide an improved tool for removing and replacing these keys which will be economical to manufacture, simple in operation, and which will instantly remove any key, regardless of its condition, without damage to either the key or the bolt.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is an end view of a conventional brake anchor bolt, with its locking key in place thereon;

Fig. 2 is a side view of the head portion of the bolt and locking key of Fig. 1;

Fig. 3 is a side elevational view of the improved tool illustrating, in broken line, its operating position relative to the bolt and key of Fig. 2;

Fig. 4 is a top plan view of the improved tool; and

Fig. 5 is an end view of the tool in place on an anchor bolt, the bolt being shown in cross-section as though cut on the line 5—5, Fig. 3.

While the invention will be found useful on any bolt having a thin, U-shaped locking key, it is more particularly designed for use on automotive brake anchor bolts. Such a bolt is illustrated at 10 on the drawing, with its U-shaped, sheet metal, locking key at 11. The key slips astride a circumferential receiving groove 12 formed about the head of the bolt 10 and having a width corresponding to the thickness of the key 11.

2

11. The opening between the two leg portions of the key 11 is slightly less than the diameter of the groove bottom so that when forced into the groove, the leg portions will separate slightly to admit the bolt and snap about the latter to lock the key in place. The key 11 is relatively wide horizontally at its middle portion, and tapers forwardly at its bottom to form narrowed extremities on the two leg portions. To remove the key, it has been heretofore necessary to pry or pound it from place.

15 The improved tool comprises two handle members, which will herein be designated for convenience an upper handle member 13 and a lower handle member 14.

20 The two handle members 13 and 14 are preferably rounded adjacent their extremities to provide a comfortable hand grip, and are vertically flattened adjacent their forward extremities to lie flat against each other about a hinge bolt 15 in plier-like arrangement.

25 The lower handle member 14 terminates in a transversely widened, downwardly curved, hooked upper jaw 16 in the bottom edge of which an upwardly curved arcuate notch 17 is formed. The radius of the notch 17 corresponds to the radius of the head of the bolt 10.

30 The upper handle member 13 terminates in a relatively wide, flat, horizontal lower jaw 18 which projects forwardly of the hooked upper jaw a distance substantially equal to the thickness of the key 11. A rearwardly extending notch 19 is formed in the forward extremity of the lower jaw 18. The width of the notch 19 is less than the width of the key 11 but greater than the width of the head of the bolt 10. The width of the upper jaw 16 is slightly less than the width of the notch 19 so that the former may pass downwardly into the latter.

35 40 Let us assume that the key 11 is in place on the bolt 10 and that it is desired to remove it with the improved tool. The jaws 16 and 18 are separated and the upper jaw 16 is rested upon the head of the bolt 10, with the notch 17 receiving the head, in close proximity to the key 11.

45 The handles 13 and 14 are now squeezed together. This brings the lower jaw 18 upwardly until the two sides of the notch 19 engage the two bulging sides of the key 11, as shown in Fig. 5. Further pressure on the handles forces the lower jaw and the key 11 upwardly and the upper jaw and the bolt 10 downwardly, resulting in snapping the key from its groove 12. The edges of the notch 19 bite into the sides of the key 11 with such force that the key wedges therein and re-

mains self-supporting in the notch after it has been removed from the bolt 10. Sufficient force can be exerted on the key to force it from the slot, regardless of its condition. If the extremities of the legs of the key are bent, they will straighten out as they are forced upwardly through the groove 12.

To replace the key with the tool, it is only necessary to reverse the tool so that the side edges of the slot 19 will engage the top of the key to force the leg portions thereof downwardly on each side of the bolt head.

In the description and claim of this invention, the handles and jaws have been referred to as "upper" and "lower," and the movements have been referred to as "upward" and "downward." It is to be understood that these are simply terms of convenience, with reference to the particular showing on the drawing. The tool will operate efficiently in any desired position and in any desired direction.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A tool for removing locking keys from brake

anchor bolts comprising: a relatively wide, flat lower jaw; an upper handle member secured to and extending upwardly and rearwardly from the middle of the rear upper surface of said lower jaw; a medially located notch extending rearward from the forward edge of said lower jaw; a hooked upper jaw; a relatively wide lower edge on said upper jaw positioned over and extending transversally of said notch and having less width than the latter; a lower handle member extending rearwardly and downwardly from said hooked upper jaw across said upper handle member; pivot means securing said handle members together at their intersection; and an upwardly curved arcuate notch formed in the said relatively wide lower edge of said hooked upper jaw, the axis of said arcuate notch lying in the vertical medial plane of the notch in said lower jaw.
